AMUSEMENT DEVICES

Louis E. Levinson, 6458 Royal Lane, Dallas, Tex.

Filed Sept. 13, 1957, Ser. No. 683,823

5 Claims. (Cl. 272—33)

This invention relates to amusement devices and more particularly to amusement devices which are actuated by the person riding the device.

An object of the invention is to provide a new and improved amusement device having a seat for carrying a rider and having means actuated by the rider for moving the seat and rider in a predetermined path.

Another object of the invention is to provide a new and improved amusement device, of the type described above, where the seat is pivotally mounted for movement about a horizontal axis.

Still another object of the invention is to provide a new and improved amusement device, of the type described above, wherein the means for moving the rider in the predetermined path are actuated by the occupant of seat by oscillating the seat about the horizontal axis.

A further object of the invention is to provide an amusement device, of the type described above, wherein the seat is biased for pivotal movement in one direction about the horizontal axis.

A still further object of the invention is to provide a new and improved amusement device having a horizontal radial beam or support mounted for rotary movement about a vertical axis, seats for riders pivotally mounted on opposite ends of the radial beam, and means actuated by pivotal oscillatory movement of the seat for rotating the radial beam.

Another object is to provide an amusement device, of the type described above, wherein the means for rotating the beam includes a bell crank lever pivotally mounted for reciprocation about a horizontal axis having one end connected to the seat and the other end connected to a spur gear in mesh with a stationary gear of a base whereby pivotal movement of the seat rotates the gear.

Still another object of the invention is to provide an amusement device, of the type described above, wherein the rear end of the seat is pivoted by foot operated means.

A further object is to provide an amusement device, of the type described above, wherein the radial beams provide foot rests for the rider.

Other objects and a fuller understanding of the invention may be had by referring to the following description and claims, taken in conjunction with the accompanying drawing in which like parts are designated by like reference characters and in which:

Figure 1 is a perspective view of an amusement device embodying the invention;

Figure 2 is a top view of the amusement device shown in Figure 1;

Figure 3 is a side view of the amusement device shown in Figure 1;

Figure 4 is an end view of one end of the radial beam and one of the seats mounted thereon;

Figure 5 is a sectional view taken on line 5—5 of Figure 2;

Figure 6 is a perspective view of a modified form of the amusement device shown in Figure 1; and

Figure 7 is an enlarged horizontal sectional view show-

2

ing one of the foot operated means of the amusement device of Figure 6 for rotating the radial beam and oscillating the seat.

This application is a continuation-in-part of my copending application, Serial No. 599,181, filed July 20, 1956, now abandoned.

Referring now particularly to Figures 1 through 5 of the drawing, the amusement device 10 includes a base 11 on which is rotatably mounted a radial substantially horizontal beam 12 on whose opposite ends are mounted seats 13 and 14. The base 11 includes three legs 15, 16 and 17 whose inner ends are disposed between two clamp plates 18 and 19 and are secured therebetween by bolts 20.

A vertical shaft 22a extends through suitable registering apertures in the clamp plates and a stationary gear 22, disposed on the upper clamp plate.

The shaft is rigidly secured to the stationary gear and the upper clamp plate in any suitable manner, as by welding, while its lower end extends through suitable apertures in the ends of bracing straps 25, 26 and 27. The straps are rigidly held to the dependent sleeve by a washer 28 and nut 29 threaded on the lower end of the shaft which is reduced to provide a downwardly facing shoulder so that the bracing straps are rigidly secured between the shoulder and the washer 28 by the nut 29. The other ends of the bracing straps 25, 26 and 27 are rigidly secured to the legs 15, 16 and 17, respectively, by bolts 28a.

The upper end of the shaft is provided with a recess 30 in which is rotatably disposed a ball bearing 31. The radial beam has a dependent barrel 33 rigidly secured thereto in any suitable manner, as by welding, which is adapted to telescope over the upper end of the vertical shaft 22a so that the beam 12 rests on the ball bearing and is thus rotatably supported by the base 11.

A gear plate 34 is rigidly affixed to the lower end of the barrel 33, as by welding, and has a shaft 34a journaled in a suitable vertical bore thereof located in an extension 36 of the gear plate which has a lower inwardly extending arm in which the lower end of the shaft 34a is journaled. A spur gear 37 is rigidly secured to the shaft 34a and meshes with the stationary gear 22. The upper end of the shaft 34a, above the gear plate, is provided with a radially extended arm 39 by means of which the spur gear may be rotated. It will be apparent that rotation of the shaft 34a will cause the spur gear to rotate about the stationary gear, since it meshes therewith, whereby the gear plate and the radial beam, which are both rigidly secured to the barrel, rotate about the vertical axis of the shaft 22a.

The shaft 34a is caused to rotate by the oscillatory movement of the seats 13 and 14 to which it is connected by a mechanical linkage which includes links 41 and 42 whose inner ends are bent about a pin 43 projecting upwardly from the arm 39 and whose outer ends are

provided with angular extensions 44 which are received in suitable apertures in the arms 45 of bell crank levers 46 and 47 and are retained therein by cotter pins 48a.

The bell crank levers 46 and 47 are pivotally mounted on vertical channel members 48 and 49, respectively, by means of bolts 50. The vertical members are rigidly secured to the radial beam at positions adjacent the opposite ends thereof by welding or the like, the radial beam passing through suitable apertures provided in the channel members.

The seats 13 and 14 are pivotally mounted on the upper ends of the vertical members 48 and 49, respectively, by means of bolts 50a which pass through registering apertures in the vertical members and the brackets 51 and 52 secured, as by screws, to the undersides of the seats 13 and 14, respectively, adjacent the forward or front ends of the seats.

Links 56 and 57 connect the rear portions of the seats

13 and 14 with the arms 58 of the bell crank levers 46 and 47. The arms 58 as well as the arms 45 are spaced outwardly or rearwardly of the vertical members to prevent contact between the links and the vertical members. The links are provided at their upper ends with horizontal sleeves 60 which are disposed in brackets 61 and 62 secured, as by screws, to the undersides of the seats 13 and 14, respectively, by means of bolts 63 and 64 which pass through registering apertures in the brackets and through the horizontal sleeves.

The lower ends of the links 56 and 57 are provided with angular extensions 65 and 66, respectively, which extend through suitable apertures in the arms 58 of the bell crank levers 46 and 47, respectively, and are retained therein by cotter pins 68.

The apertures in the arms 58 in which the extensions 65 and 66 of the links 56 and 57 are received are preferably somewhat larger than the extensions to permit a certain degree of movement of the extensions in the apertures to prevent binding thereof due to the arcuate movement of the arms 58 about the bolts 50.

The forward ends of the seats 13 are biased downwardly by springs 70 and 71 whose upper ends are secured to the seats by means of brackets 72 secured to the seats in any suitable manner and whose lower ends are secured to the radial beam by means of eye screws 73 threaded in suitable bores in the radial beam.

The seats are provided with vertical members 75, which may be formed to represent the head of a horse or other animal and which are provided with handles 76 which the rider may hold with both hands to help support himself on the seat.

In use, the riders sit on a seat with their feet resting on the radial beam on opposite sides of each of the vertical members 48 and 49. The riders move alternately forward and back causing the seats 13 and 14 to oscillate or pivot about the bolts 50a, the weight of each rider being effective to move downwardly the rear portion of his seat. In addition, each rider may brace his feet on the radial beam and pull backward on the handle 76 to accelerate such downward movement of the rear portion of his seat. Downward movement of the forward portion of the seat is achieved by pushing on the handles 76 forwardly although this is not necessary when two riders are on the amusement device since the bell crank levers 46 and 47 are so positioned relative to one another that as the rear portion of one seat is moving downwardly the rear portion of the other seat is moving upwardly so that the weight of one rider acting on the rear portion of one seat to move it downwardly is effective to move the rear portion of the other seat upwardly.

As the rear portion of one seat, say seat 14, is moved downwardly, the link 57 pivots the bell crank lever in a clockwise direction to Figure 1 which causes the link 42 to be moved outwardly. As a result, the lever 39 and the pin 43 are rotated in a counterclockwise manner, Figure 1, through one hundred eighty degrees. Rotation of the pin 43, of course, causes the spur gear 37 to rotate and this moves or rotates the radial beam about the vertical axis of the vertical shaft 22a. During such movement of the rear portion of the seat 14, seat 13 is raised to its uppermost position due to the action of the link 41 which caused the bell crank lever 46 to rotate in a clockwise manner and to the action of the spring 70. The rider on the seat 13 now allows his weight to bear down on the rear portion of the seat 13 and simultaneously may pull backwardly on the handle 76 thus causing the rear portion of the seat 13 to move downwardly and thus cause the bell crank lever 46 to rotate or pivot in a counterclockwise manner about its bolt 50. As a result, the link 41 is moved outwardly causing the lever 39 to continue to rotate in a clockwise direction through another one hundred eighty degrees. Continued repetition of this cycle of operation causes the radial beam to rotate continuously about the vertical axis of the shaft

22a as the riders move upwardly and downwardly with the seats 13 and 14.

It will be apparent that a minimum of force is necessary to attain rotation of the radial beam since a mechanical advantage results between the seat and the stationary gear since arms 58 of the bell crank levers are longer than the arms 45 and the spur gear of course is smaller than the stationary gear. In addition the arm 39 is larger than the radius of the spur gear. Due to this combined 10 mechanical advantage of the linkages between the seat and stationary gear, rotation of the radial beam is effected easily and smoothly with an expenditure of a minimum of force by the riders. If desired the springs 70 and 71 can be dispensed with.

It will now be apparent that the new and improved amusement device includes a radial beam mounted on a base for rotation about a vertical axis and that a pair of seats are pivotally mounted adjacent the opposite ends of the beam. It will be further seen that the base is provided with a stationary gear 22 which meshes with a rotatable spur gear 37 rotatably mounted on the beam by means of a gear plate 34 whereby rotation of the spur gear causes the radial beam to rotate about a vertical axis. It will also be seen that the spur gear is connected 20 to the rear portions of the seats through mechanical linkages which includes bell crank levers mounted on the beam by means of the vertical members 48 and 49 for pivotal movement about horizontal axes whereby 25 pivotal movement of the seats about horizontal axes perpendicular to the pivotal axes of the bell crank levers causes rotation of the spur gear.

It will also be seen that the riders face the direction in which they are moved.

In Figures 6 and 7 is illustrated a modified form of 35 the amusement device shown in Figures 1 through 5. The amusement device 100 differs from the amusement device 10 in that each bell crank lever 45 and 58 is provided with forwardly extending arms 101 and 102 having slots 103 in which are received the angular extensions 104 of pedal levers 105 and 106. The pedal levers 105 and 106 are provided with pedal portions 107 which are engaged by the feet of the riders. The pedal levers are pivoted intermediate their ends on a shaft 109 which extends through suitable apertures in a U-bracket 110 rigidly secured to the vertical members 48 and 49 in any suitable way, as by welding. Spacer sleeves 111 and 112 are disposed on the shaft and between the bracket and the pedal levers to hold the pedal levers properly positioned on the shaft.

It will be apparent that each rider pushes the pedal portions 107 of the pedal lever 105 and 106 alternately downwardly to cause pivotal oscillatory movement of the brackets 46 and 47 which thus causes the seats to oscillate about their pivots 50a and simultaneously causes the radial beam to rotate. Although springs 70 and 71 are provided they may be dispensed with.

It will be apparent that various changes in the construction of the amusement device can be made without departing from the invention and it is intended, therefore, to cover in the appended claims all such changes or modifications as fall within the true spirit and scope of the invention.

What I claim is new and desire to secure by Letters Patent of the United States is:

65 1. An amusement device including a base; a beam mounted on said base for rotation about a vertical axis; a seat pivotally mounted on said beam for oscillatory movement about a first substantially horizontal axis; and drive means for rotating said beam about the vertical axis, said drive means comprising a bell crank lever having two arms extending substantially perpendicularly relative to one another pivotally mounted on said beam for oscillatory movement about a second substantially horizontal axis perpendicular to said first horizontal axis, means 70 connecting one of said arms to said seat, cooperating 75

gear means on said beam and said base, and means connecting the other of said arms to said gear means.

2. An amusement device including a base; a beam mounted on said base for rotation about a vertical axis; a seat pivotally mounted on said beam for oscillatory movement about a first substantially horizontal axis; and drive means for rotating said beam about the vertical axis, said drive means comprising a bell crank lever having two arms extending substantially perpendicularly relative to one another pivotally mounted on said beam for oscillatory movement about a second substantially horizontal axis perpendicular to said first horizontal axis, means connecting one of said arms to said seat, cooperating gear means on said beam and said base, means connecting the other of said arms to said gear means, and resilient means biasing said seat for movement in one direction about said first horizontal axis.

3. An amusement device including a base; a beam mounted on said base for rotation about a vertical axis; a seat pivotally mounted on said beam for oscillatory movement about a first substantially horizontal axis; and drive means for rotating said beam about the vertical axis, said drive means comprising a bell crank lever having two arms extending substantially perpendicularly relative to one another pivotally mounted on said beam for oscillatory movement about a second substantially horizontal axis perpendicular to said first horizontal axis, means connecting one of said arms to said seat, cooperating gear means on said beam and said base, means connecting the other of said arms to said gear means, and foot operated mounted arm on said beam for imparting oscillatory movement to said bell crank lever.

4. An amusement device including a base; a beam mounted on said base for rotation about a vertical axis; a seat pivotally mounted on said beam for oscillatory movement about a first substantially horizontal axis; and drive means for rotating said beam about the vertical axis, said drive means comprising a bell crank lever having two arms extending substantially perpendicularly rela-

tive to one another pivotally mounted on said beam for oscillatory movement about a second substantially horizontal axis perpendicular to said first horizontal axis, means connecting one of said arms to said seat, cooperating gear means on said beam and said base, means connecting the other of said arms to said gear means, and resilient means biasing the front portion of the seat downwardly, said means connecting one of said arms to the seat being connected to said seat at a point rearwardly of said first horizontal axis.

5. An amusement device including a base; a beam mounted on said base for rotation about a vertical axis; a seat pivotally mounted on said beam for oscillatory movement about a first substantially horizontal axis; and drive means for rotating said beam about the vertical axis, said drive means comprising a bell crank lever having two arms extending substantially perpendicularly relative to one another pivotally mounted on said beam for oscillatory movement about a second substantially horizontal axis perpendicular to said first horizontal axis, means connecting one of said arms to said seat, cooperating gear means on said beam and said base, means connecting the other of said arms to said gear means, resilient means biasing the front portion of the seat downwardly, said means connecting one of said arms to the seat being connected to said seat at a point rearwardly of said first horizontal axis, and foot operated lever mounted on said beam for imparting oscillatory movement to said bell crank lever.
